US0D1058137S

(12) **United States Design Patent** (10) **Patent No.:** **US D1,058,137 S**
(45) **Date of Patent:** **** Jan. 21, 2025**

(54) **INSOLE**

(71) Applicant: **Zhenzhen Guo**, Dongguan (CN)

(72) Inventor: **Zhenzhen Guo**, Dongguan (CN)

(**) Term: **15 Years**

(21) Appl. No.: **29/960,546**

(22) Filed: **Aug. 30, 2024**

(51) LOC (15) Cl. **02-04**

(52) U.S. Cl.

USPC **D2/961**

(58) **Field of Classification Search**
